UNITED STATES PATENT OFFICE.

WILLIAM H. APPLEBY, OF CHICAGO, ILLINOIS.

LATCH.

1,304,244.

Specification of Letters Patent.

Patented May 20, 1919.

Application filed May 4, 1918. Serial No. 232,490.

To all whom it may concern:

Be it known that I, WILLIAM H. APPLEBY, a citizen of the United States, residing at Chicago, in the county of Cook and State 5 of Illinois, have invented a certain new and useful Improvement in Latches, of which the following is a specification.

My invention relates to latches, frequently known in the trade as locks, especially for the doors of automobiles and other vehicles, although it will be understood that the device is applicable to a variety of situations where a simple, effective, and inexpensive device is desired.

15 The general object of the invention is to provide a structure having a minimum number of parts and one which may be applied to the door with a minimum amount of labor. The specific objects, relating to 20 structural expedients, will be understood as the description proceeds.

I accomplish my objects by the mechanism illustrated in the accompanying drawings, in which—

25 Figure 1 is a face view of a structure embodying my invention. It is shown mounted upon a door.

Fig. 2 is a vertical sectional view on the line 2—2, Fig. 1.

30 Fig. 3 is a plan section on the line 3—3, Fig. 1.

Fig. 4 is a face view of a similar device, showing a modified form of mechanism for operating the main lever.

35 Fig. 5 is a plan section on the line 5—5, Fig. 4.

Fig. 6 is an edge view of the face plate shown in Figs. 1 to 5.

40 Fig. 7 is an edge view of a face plate which is similar to the one shown in Fig. 6, except that the barrel is rectangular instead of cylindrical in cross section.

Fig. 8 is a face view of a face plate in which the barrel instead of being located at 45 the lower end of the plate is located between the upper and lower ends.

Fig. 9 is a vertical section on the line 9—9, Fig. 8.

Fig. 10 is an edge view of the form of 50 face plate shown in Figs. 8 and 9.

Fig. 11 is a perspective view from the inner side of a face plate showing the type of lock illustrated in Figs. 1 to 3.

Fig. 12 is a perspective view illustrating 55 the manner of mounting the device upon the door.

Fig. 13 is an end view of the inner end of the barrel showing the manner of forming the tongues or stops for backing up the 60 spring.

Similar numerals refer to similar parts throughout the several views.

Referring first to the form shown in Figs. 1, 2, 3, 6, 11, 12 and 13, the face plate 1 is designed to lie flush with the inside 65 of the door. It consists preferably of sheet metal, the lower edge of which is bent up to form a cylindrical barrel 2. This barrel is tangential to the plane of the plate and forms a guide for the bolt 3. The bolt is 70 also cylindrical and has a beveled nose 3^a operating in the usual way. The inner end is backed up by a helical compression spring 4, one end of which abuts the bolt and the other end abuts the stops 5. These 75 stops are formed by slotting the inner end of the barrel for a short distance and turning inward the tongues, thus formed, as shown in detail in Fig. 13. By preference, the rear end 3^b of the bolt is trunco conical, as best shown in Fig. 3. A flat bottomed recess 7 is formed in the side of the bolt for accommodating the lower end of the main lever 8. This lever is pivoted to the back of the face plate by means of 80 a pin 10. The result of this construction is that the lever not only engages the bolt to retract it, but prevents it from rotating about its longitudinal median line as an axis. A slot 12 is formed in the top of the 85 barrel for the entrance of the lever, said slot being elongated sufficiently to permit the necessary movement. At its upper end the lever has a handle 14 which projects through the slot 15 in the face plate, and 90 affords means whereby the lever may be operated.

In practice, assuming the latch is for a vehicle door, it is mounted upon the inside 100 of the door (here indicated by the reference numeral 17). If of wood, the door frame or jamb 18 is provided with a striking plate 19 of any suitable form. A stop 20 is provided, usually on the door frame, for limiting the inward movement of the door. The 105 operation will now be readily understood. A counter-sink 21 is usually formed on the inner surface of the door for accommodating the face plate, although the plate may, with equal effect, be simply fastened to the plane 110 surface of the door. A rabbet or chamber 22 is made for accommodating the lever 8

in its different positions. A bore 23 is cut in the door at the lower end of the countersink 21 for receiving the barrel 3. By preference, this bore is of such a diameter that the barrel fits snugly in it. When these various recesses have been formed in the door, the device may be inserted by merely sliding the barrel lengthwise in the bore. As the barrel is cylindrical, the upper portion of the face plate may be held away from the door—that is, at an angle to it, as shown in Fig. 12. When the device has thus been slipped horizontally to position, the face plate is simply swung up vertically into contact with the surface of the door, after which it is screwed to the door, the plate being provided with screw holes 25 for the purpose. It will be noted by referring to Fig. 12 that by using this form of device the edge of the door is left intact, except in so far as it is completely filled by the face plate itself; that is to say, it is not necessary to cut away any part of the edge of the door (for example, at the point 26, 12) to permit the lever or any other part of the device to pass when the device is being inserted. Consequently, no filler plates or flanges are necessary to impart a finished appearance to the installation. This is true notwithstanding the fact that the edge of the plate itself comes flush with the end of the door. After the lock has been installed, the bolt may be retracted by manipulating the handle 14 of the lever; and by pivoting the lever between its ends, as best shown in Figs. 1 and 11, the necessary travel of the bolt may be obtained by a comparatively slight movement of the handle. Thus the slot 15 is comparatively short.

From the foregoing, it will be evident that the device consists of extremely few parts; viz., the face plate with its integral barrel, the bolt, the spring, and the lever. This reduces the cost of manufacture to a minimum, and reduces the amount of labor required to install it. No loose plates or pieces are necessary to impart a finished appearance to the job after the face plate has been secured in position, and the device may be said to be a "flangeless" latch or lock. The barrel gives a long bearing for the bolt and a curved bearing surface, well adapted to withstand the shocks of many slammings of the door and, viewed as a whole, there is, practically speaking, nothing to wear out. The device may also be said to have an "anti rattle" construction, for it will be noted that the trunco conical or beveled inner end of the bolt seats snugly in the forward end of the helical spring and that the thing which limits the outward movement of the bolt is the engagement of the lever handle 14 with the end of the slot 15. Thus, everything is tight and by making the spring reasonably strong, there is no danger

that the vibration of the vehicle will produce any rattling of any of the parts.

The form shown in Fig. 7 is similar to the one hereinabove described, except that the barrel 30 instead of being cylindrical is rectangular in cross section.

In Figs. 8, 9 and 10 the barrel 35 instead of being formed at the lower end of the plate is formed at an intermediate point. In this event, the lever 36 is pivoted at its lower end 37.

In the form shown in Figs. 4 and 5, the barrel is formed at the lower end of the face plate and is cylindrical, but the main lever 8 instead of being operated by a handle at its upper end is operated by a lever 40 journaled in a sleeve 41, fastened to the face plate, and having at its inner squared end an arm 42 which normally lies in contact with the rear edge of the main lever. The arrangement is such that if the lever 40 is rotated in either direction from normal, it will retract the bolt. It is desirable that arm 42 have a flange 43 which overlaps the lever and thus acts as a keeper to prevent the lever from becoming disengaged from the arm.

Having thus described my invention, what I claim as new and desire to secure by Letters Patent, is:

1. A door latch having a plate adapted to lie substantially flush with the surface of the door, a barrel formed on said plate and lying behind the plane thereof for the purpose of being embedded in the door, a bolt 100 slidable in said barrel, and a handle for actuating said bolt, said handle passing from the bolt forward through and beyond the plane of the plate whereby it may be grasped on the side of the plate opposite 105 to the barrel.

2. A door having a plate adapted to lie substantially flush with the surface of the door, a barrel formed on said plate and lying behind the plane thereof for the purpose of being embedded in the door, a bolt 110 slidable in said barrel, and a handle for actuating said bolt, the handle passing from the bolt forward through and beyond the plane of the plate, and the plate being 115 slotted to accommodate the plate-penetrating portion of the handle.

3. A door latch having a plate adapted to lie substantially flush with the surface of the door, a barrel formed tangential with 120 the plate and adapted to extend back into the body of the door, a bolt slidable in the barrel, a lever behind the plate and movable in a plane parallel and adjacent thereto, said lever engaging the bolt and there being an opening in the barrel adjacent to the plate for permitting the movement of the lever, the lever passing forward through the plane of the plate whereby it may be 125 grasped from a point in front of it.

4. A door latch having a plate adapted to lie substantially flush with the surface of the door, a barrel formed tangential with the plate at one edge thereof, and adapted 5 to be embedded in the body of the door, a bolt slideable in the barrel, a lever mounted on the back of the plate and movable in a plane parallel and adjacent thereto, said lever engaging the bolt, and the barrel hav-
 10 ing an opening for accommodating the lever, a handle at the side of the plate opposite to the barrel, said handle being fastened to the lever and the plate having a slot through which the handle may reach the le-
 15 ver.
5. A door latch having a plate adapted to lie parallel with the plane of the door and substantially flush with the surface thereof, a bolt, a barrel adapted to be embedded in 20 the body of the door and being formed by bending the plate backward upon itself so the raw edge lies back of the plate, said plate having an opening in it, and a handle in front of the plate and passing through 25 said opening to the bolt for manipulating the latter.
6. A latch comprising a face plate bent to form a cylindrical barrel, a cylindrical bolt slideable in said barrel, a lever for retracting 30 said bolt, said lever being adapted to prevent rotation of the bolt in the barrel and being pivoted to the face plate.
7. A latch comprising a face plate curved at one part to form a cylindrical barrel lo-
 35 cated behind the front surface of the plate, a cylindrical bolt sliding in said barrel, a lever for actuating said bolt, said lever being pivoted to the back of the plate and adapted to prevent the bolt from rotating,
- 40 and a handle in front of the plate for manipulating the lever, said plate having an opening through which the handle connects with the lever.
8. A latch comprising a bolt, a sheet metal 45 face plate, one portion whereof is bent to form a barrel behind the plate for receiving the bolt, a helical spring engaging the back end of the bolt for projecting said bolt, and a back stop for the bolt formed by infold-
- ing a portion of the barrel at a point behind 50 the bolt.
9. A latch comprising a sheet metal face plate, one end of which is rolled backward to form a barrel, a bolt sliding in said barrel, and a helical spring backing up said 55 bolt, the back end of the barrel having an integral tongue bent inward to form a back-ing for the spring.
10. A latch comprising a face plate, a cy-
 lindrical barrel at the back thereof, a cylin- 60 drical bolt fitting slidably in said barrel, and an operating lever mounted to swing in a plane parallel to the plane of the plate, behind said plate, the bolt having a flat bot-
 tom depression formed in its side adapted 65 to accommodate the lever, whereby the movement of the lever causes the bolt to slide in the barrel and the presence of the lever prevents the bolt from rotating.
11. A latch having a face plate, a bolt, a 70 guide for said bolt substantially surround-
 ing it and formed integral with said plate, a lever pivoted to the back of the plate and adapted to actuate the bolt, a spring back-
 ing up the bolt, and a stop on the face plate 75 for limiting the movement of the lever un-
 der the action of the spring, whereby the parts are prevented from rattling.
12. A latch having a face plate, a cy-
 lindrical barrel integral therewith, a cylindri- 80 cal bolt fitting slidably within the barrel, the bolt being beveled at the inner end, and a helical spring backing up the bolt and snugly fitting on the beveled end of the bolt for preventing rattling.
13. A flangeless latch having a sheet metal 85 face plate bent up cylindrically at one end to form a cylindrical guide for the bolt, a bolt fitting in said guide, a lever pivoted to the back of the plate, the bolt having a flat depression in the side, and the lever passing between the bottom of the depression and the back of the plate and thereby preventing the bolt from rotating.
- In witness whereof I have hereunto sub- 90 scribed my name.

WILLIAM H. APPLEBY.
